US0D1061724S

(12) **United States Design Patent** (10) **Patent No.:** **US D1,061,724 S**
(45) **Date of Patent:** **** Feb. 11, 2025**

(54) **BUILDING BLOCK**

(71) Applicant: **Peixia Chen**, Guangdong (CN)

(72) Inventor: **Peixia Chen**, Guangdong (CN)

(**) Term: **15 Years**

(21) Appl. No.: **29/975,212**

(22) Filed: **Nov. 27, 2024**

Related U.S. Application Data

(63) Continuation-in-part of application No. 29/942,309, filed on May 15, 2024.

(51) **LOC (15) Cl.** **21-01**

(52) **U.S. Cl.**

USPC **D21/499**; D21/404
